UNITED STATES PATENT OFFICE

2,423,433

THREAD GUIDE RACKING MECHANISM

Roy C. Amidon, Reading, Pa., assignor to Vanity Fair Mills, Inc., Reading, Pa., a corporation of Pennsylvania

Original application October 16, 1943, Serial No. 506,561. Divided and this application April 23, 1945, Serial No. 589,859

21 Claims. (Cl. 66—86)

1

My invention which relates generally to warp knitting machines, particularly has reference to the means for racking the thread guides of such machines.

More specifically it is an object of my present invention to improve the racking means used on tricot machines and to that end the thread guide bars are actuated in their racking movement by a pattern wheel or cam and a racking lever so as to move the guide bar in one direction while another pattern wheel or cam moves the same bar in the other direction, one pattern wheel or cam acting as a counter or follower for the other pattern wheel or cam, the acting cam being supported, in addition to its counter, by spring pressure. The connections between the racking lever and the guide bar are so arranged that there is a direct contact between the two so that when the bar is moved in one direction it is pushed and held in position by its counter connection and in the reverse direction it is pulled and held in position by its pushing support.

Other objects of the invention will in part be obvious and in part be pointed out hereinafter.

To the attainment of the aforesaid object and ends the invention still further resides in the novel details of construction, combination and arrangement of parts, all of which will be first fully described in the following detailed description, and then be particularly pointed out in the appended claims, reference being had to the accompanying drawings, in which:

Fig. 1 is a front elevation of a portion of a warp-knitting machine embodying my invention.

Fig. 2 is an end elevation of the same on a reduced scale.

Fig. 3 is a detail section on the line 3—3 of Fig. 2.

Fig. 4 is a detail section on the line 4—4 of Fig. 2.

Fig. 5 is a detail section on line 5—5 of Fig. 3.

In the drawings in which like letters and numerals of reference indicate like parts in all the figures, 1 designates an end frame of the machine and 3 the longitudinal pipes that connect the end frames together.

Vertical longitudinally disposed brackets 5 are secured on the end frame 1 shown in Figs. 1 and 2.

6 and 7 indicate, respectively, the lower and upper cam shafts of the machine shown (i. e., that disclosed in my application for patent filed October 16, 1943, Serial No. 506,561, of which this application is a division). The rock shaft on which the front thread guide frame 100, 101, 102

2

is swingably and reciprocatingly mounted is shown at 13 in Figs. 1 and 2.

Referring now to Figs. 1 and 2, it will be observed that the racking bar 100 has a fitting 107 attached to it at one end. The back racking bar also has a similar fitting 108 at the corresponding end. Mounted, one above the other, in the brackets 5 are shafts 109, 110, 111, the shaft 110 being the master pattern wheel shaft, and the shaft 109 being a shaft on which the racking levers 119 and 120 are rockably mounted. The shafts 110 and 111 are geared together by spur gears 112 and the shaft 110 is driven from cam shaft 6 through worm gears 113 and 114. 115 indicates the master pattern wheel and 116 the follower pattern wheel which contact, respectively, the rollers 131 and 132 on the yoke 129 of the lever 119. The rollers 133 and 134 on the yoke 130 of the lever 120, cooperate, respectively, with the master pattern wheel 117 and follower pattern wheel 118 (Fig. 2) on the shaft 110.

A longitudinally adjustable connecting rod 121 has one end pivoted at 122 to the lever 119 and its other end pivoted at 123 to the fitting 107. A two-piece push rod 124 having a turnbuckle connection 213 has its ends of semi-spherical shape to fit corresponding sockets in the lever 119 and in the fitting 107 (see dotted lines 215 in Fig. 3). By this construction any play which might take place between the lever 119 and the front thread guide frame can be taken up. A longitudinally adjustable connecting rod 125 is pivoted at one end, as at 126, to the lever 120 and at the other end, as at 127, to the fitting 108 of the back thread guide bar (Fig. 1). A two piece push rod 128, having a turnbuckle 214, has its semi-spherical ends set into corresponding sockets, (similar to the rod 124) in the lever 120 and the fitting 108.

40 The yokes 129 and 130 each carries two slide rods 138 having rollers 137 and springs 139 which constantly force the rollers into contact with take-up cams 135 and 136, respectively.

Referring again to Figs. 3 and 4, it will be seen that the connecting or pull rod 121 is offset. The offset portion 219 is apertured as indicated by dotted lines 220 in Fig. 3, and the rod 124 passes through the aperture.

Power is applied by any well known or suitable means (not shown) to shaft 6 as a first motion shaft of the machine.

From the foregoing description taken in connection with the accompanying drawings it will be seen that the racking movements take place by positive push pull actions, without the use of

pull-back springs and is at all times free from lost motion or back lash, thus providing for uniform racking in both directions, and it is thought the construction, operation and advantages of my invention will be clear to those skilled in the art.

What I claim is:

1. In a machine of the class described, where-
in a thread guide bar is racked; means for racking said bar, which means include, a pattern-
wheel shaft, pattern-wheels on said shaft; a piv-
oted racking lever having a yoke to pass said pat-
tern-wheel shaft and a second shaft passing

through said yoke, gears connecting said shafts,
cams on said second shaft, spring pressed rollers
carried by said yoke to engage said cams on op-
posite sides of said second shaft, and a connec-
tion from said racking lever to the thread guide
bar.

2. In a flat knitting machine employing knock-
over sinkers, needles and thread guides; a thread
guide racking mechanism which includes a recip-
rocatable thread guide carrier; a racking lever; a
push-pull connection between said lever and said
carrier; a pattern wheel shaft; a pair of pattern
wheels on said shaft; a roller on said lever for
engaging one pattern wheel and another roller on
said lever for engaging the other pattern wheel
at the side of the pattern wheel shaft opposite
the first roller, by virtue of all of which the thread
guide carrier is alternately pushed in one direc-
tion and pulled in the opposite direction for racking
purposes.

3. A knitting machine employing knock-over
sinkers, needles and thread guides; a thread
guide racking mechanism which includes a recip-
rocatable thread guide carrier; a racking lever; a
push-pull connection between said lever and said
carrier, said push-pull connection including a
longitudinally adjustable connecting rod pivoted
to said lever and to said carrier; a pattern wheel
shaft; a pair of pattern wheels on said shaft; a
roller on said lever for engaging one pattern
wheel and another roller on said lever for engag-
ing the other pattern wheel at the side of the
pattern wheel shaft opposite the first roller, by
virtue of all of which the thread guide carrier
is alternately pushed in one direction and pulled
in the opposite direction for racking purposes.

4. A knitting machine employing knock-over
sinkers, needles and thread guides; a thread guide
racking mechanism which includes a reciprocatable
thread guide carrier; a racking lever; a push-pull
connection between said lever and said carrier,
said push-pull connection including a longitudinally
adjustable connecting rod pivoted to said lever
and to said carrier, and a second rod seated at one
end in said lever and at its other end in said
carrier; a pattern wheel shaft; a pair of pattern
wheels on said shaft; a roller on said lever for
engaging one of said pattern wheels and another
roller on said lever for engaging the other pattern
wheel at the side of the pattern wheel shaft oppo-
site the first roller, by virtue of all of which the
thread guide carrier is alternately pushed in one
direction and pulled in the opposite direction for
racking purposes.

5. In a knitting machine employing knock-over
sinkers, needles and thread guides; a thread guide
racking mechanism which includes a reciprocatable
thread guide carrier; a racking lever; a push-pull
connection between said lever and said carrier,
said push-pull connection comprising a pull
rod connected to said lever at one end and to said
carrier at the other end, and a push rod held be-

tween and engaging said lever and said carrier
and located adjacent said pull rod; a pattern
wheel shaft; a pair of pattern wheels on said
shaft; a roller on said lever for engaging one pat-
tern wheel and another roller on said lever for
engaging the other pattern wheel at the side of
the pattern wheel shaft opposite the first roller,
by virtue of all of which the thread guide carrier
is alternately pushed in one direction and pulled
in the opposite direction for racking purposes.

6. In a knitting machine employing knock-over
sinkers, needles and thread guides; a thread guide
racking mechanism which includes a reciprocatable
thread guide carrier; a racking lever; a push-pull
connection between said lever and said carrier,
said push-pull connection comprising a pull
rod connected to said lever at one end and to
said carrier at the other end, a push rod held
between and engaging said lever and said carrier
and located adjacent said pull rod; means for
taking up wear in said push-pull connections; a
pattern wheel shaft; a pair of pattern wheels on
said shaft; a roller on said lever for engaging
one of said pattern wheels and another roller on
said lever for engaging the other of said pattern
wheels at the side of the pattern wheel shaft oppo-
site the first roller, by virtue of all of which the
thread guide carrier is alternately pulled in one
direction and pushed in the opposite direction for
racking purposes.

7. In a knitting machine employing a reciprocatable
thread guide carrier bar: the improve-
ment which includes a racking lever; a push-pull
connection between said lever and said carrier
bar, said connection including a push bar and
a pull bar and means for taking up lost motion
between said bars and said lever and said carrier
bar; and positively acting means to rock said
lever in two directions to rack the thread guide.

8. In a knitting machine employing a reciprocatable
thread guide carrier bar: the improve-
ment which includes a racking lever; a push-pull
connection between said lever and said bar; posi-
tively acting means to rock said lever in two
directions to rack the thread guide carrier bar,
said positively acting means including a pattern
wheel shaft, two oppositely disposed pattern
wheels on said shaft, a roller on said lever to
engage each pattern wheel, whereby said lever is
rocked in both directions by said pattern wheels,
thereby to impart, alternately, a push and a pull
on said carrier bar.

9. In a knitting machine employing a reciprocatable
thread guide carrier bar: the improve-
ment which includes a racking lever; a push-pull
connection between said lever and said bar; a
pattern wheel shaft; two oppositely disposed pat-
tern wheels on said shaft; a roller on said lever
for engaging each pattern wheel, whereby said
lever is rocked in both directions by said pattern
wheels to impart, alternately, a push and a pull
on said carrier bar; and means continuously
acting to maintain said rollers in contact with
their respective pattern wheels.

10. In a knitting machine employing a reciprocatable
thread guide carrier bar: the improve-
ment which includes a racking lever; a push-pull
connection between said lever and said bar; posi-
tively acting means to rock said lever in two
directions to rack the thread guide carrier bar,
said positively acting means including a pattern
wheel shaft, two oppositely disposed pattern
wheels on said shaft, a roller on said lever to en-
gage each pattern wheel, whereby said lever is
rocked in both directions by said pattern wheels,

thereby to impart, alternately, a push and a pull on said carrier bar; a second shaft geared to said pattern wheel shaft; a cam on said second shaft; and spring pressed rollers on said lever engaging said cam at opposite places, by virtue of which any wear in the pattern wheels is compensated.

11. In a knitting machine employing a reciprocatable thread guide carrier bar: the improvement which includes a racking lever; a push-pull connection between said lever and said carrier bar, said push-pull connection including a longitudinally adjustable connecting rod pivotally connected at one of its ends to said lever and at its other end to said carrier bar, and a longitudinally adjustable push rod between and engaging said lever and said carrier bar; and positively acting means to rock said lever in two directions to rack the thread guide carrier bar.

12. In a knitting machine employing a reciprocatable thread guide carrier bar: the improvement which includes a racking lever; a push-pull connection between said lever and said carrier bar, said push-pull connection including a longitudinally adjustable connecting rod pivotally connected at one of its ends to said lever and at its other end to said carrier bar, and a longitudinally adjustable push rod between and engaging said lever and said carrier bar; and positively acting means to rock said lever in two directions to rack the thread guide carrier bar, said positively acting means including a pattern wheel shaft, two oppositely disposed pattern wheels on said shaft, a roller on said lever to engage each pattern wheel, whereby said lever is rocked in both directions by said pattern wheels, thereby to impart, alternately, a push and a pull on said carrier bar.

13. In a knitting machine employing a reciprocatable thread guide carrier bar: the improvement which includes a racking lever; a push-pull connection between said lever and said carrier bar, said push-pull connection including a longitudinally adjustable connecting rod pivotally connected at one of its ends to said lever and at its other end to said carrier bar, and a longitudinally adjustable push rod between and engaging said lever and said carrier bar; a pattern wheel shaft; two oppositely disposed pattern wheels on said shaft; a roller on said lever for engaging each pattern wheel, whereby said lever is rocked in both directions by said pattern wheels to impart, alternately, a push and a pull on said carrier bar; and means continuously acting to maintain said rollers in operative contact with their respective pattern wheels.

14. In a knitting machine employing a reciprocatable thread guide carrier bar: the improvement which includes a racking lever; a push-pull connection between said lever and said carrier bar, said push-pull connection including a longitudinally adjustable connecting rod pivotally connected at one of its ends to said lever and at its other end to said carrier bar, and a longitudinally adjustable push rod between and engaging said lever and said carrier bar; means to rock said lever in two directions to rack the thread guide carrier bar, said means including a pattern wheel shaft, two oppositely disposed pattern wheels on said shaft, a roller on said lever to engage each pattern wheel, whereby said lever is rocked in both directions by said pattern wheels, thereby to impart, alternately, a push and a pull on said carrier bar; a second shaft geared to said pattern wheel shaft; a cam on said second shaft; and spring pressed rollers on

said lever engaging said cam at opposite places, by virtue of which wear on the pattern wheels is compensated.

15. In a knitting machine: a longitudinally reciprocating and transversely moving racking bar; a racking lever; a pattern wheel shaft having pattern wheels for positively swinging said lever in two directions; rollers on said lever engaging said pattern wheels, one roller engaging one of said pattern wheels at one side of the axis of said shaft and the other roller engaging the other pattern wheel at the other side of the axis of said shaft; and a push-pull connection between said lever and said racking bar.

16. In a knitting machine: a longitudinally reciprocating and transversely moving racking bar; a racking lever; a pattern wheel shaft having pattern wheels for positively swinging said lever in two directions; rollers on said lever engaging said pattern wheels; and a push-pull connection between said lever and said racking bar, said push-pull connection comprising a pull rod pivoted at one of its ends to said lever and at its other end to said racking bar, and a push rod engaging said lever at a point above the pivotal connection of the pull rod to said lever and engaging said racking bar at a point below the pivotal connection of the pull rod to said bar.

17. In a knitting machine: a longitudinally reciprocating and transversely moving racking bar; a racking lever; a pattern wheel shaft having pattern wheels for positively swinging said lever in two directions; rollers on said lever engaging said pattern wheels; and a push-pull connection between said lever and said racking bar, said push-pull connection comprising a pull rod pivoted at one of its ends to said lever and at its other end to said racking bar, and a push rod engaging said lever at a point above the pivotal connection of the pull rod to said lever and engaging said racking bar at a point below the pivotal connection of the pull rod to said bar, said pull rod being offset and said push rod passing through an aperture in the offset of said pull rod.

18. In a knitting machine: a longitudinally reciprocating and transversely moving racking bar with thread guides; a racking lever; a pattern wheel shaft having pattern wheels for positively swinging said lever in two directions; rollers on said lever engaging said pattern wheels, one roller engaging one of said pattern wheels at one side of the axis of said shaft and the other roller engaging the other pattern wheel at the other side of the axis of said shaft; means for adjusting the position of the rollers on said lever to center the thread guides between the knitting needles of the machine; and a push-pull connection between said lever and said racking bar.

19. In a knitting machine: a longitudinally reciprocating and transversely moving racking bar carrying thread guides; a racking lever; a pattern wheel shaft having pattern wheels for positively swinging said lever in two directions; rollers on said lever engaging said pattern wheels; means for adjusting the position of the rollers on said lever to center the thread guides carried by the racking bar between the knitting needles of the machine; and a push-pull connection between said lever and said racking bar, said push-pull connection comprising a pull rod pivoted at one of its ends to said lever and at its other end to said racking bar, and a push rod engaging said lever at a point above the pivotal connection of the pull rod to said lever and en-

gaging said racking bar at a point below the pivotal connection of the pull rod to said bar.

20. In a knitting machine: a longitudinally reciprocating and transversely moving racking bar carrying thread guides; a racking lever; a pattern wheel shaft having pattern wheels for positively swinging said lever in two directions; rollers on said lever engaging said pattern wheels; means for adjusting the positions of said rollers on said lever to center the thread guides between the knitting needles of the machine; and a push-pull connection comprising a pull rod pivoted at one of its ends to said lever and at its other end to said racking bar, and a push rod engaging said lever at a point above the pivotal connection of the pull rod to said lever and engaging said racking bar at a point below the pivotal connection of the pull rod to said bar, said pull rod being offset and said push rod passing through an aperture in the offset of said pull rod.

21. In a knitting machine employing a reciprocatable thread guide carrier bar, the improvement which includes: a racking lever having a yoke; a push-pull connection between said carrier bar and said lever; two intergeared shafts, one

of which is a pattern wheel shaft, said shafts passing through said yoke; pattern wheels on said pattern wheel shaft; a roller on said lever engaging one of said pattern wheels at one side of its axis; a roller on said lever engaging the other of said pattern wheels at the other side of the axis; and means on the other of said shafts and on said yoke for maintaining contact between said pattern wheels and said pattern-wheel-engaging rollers.
